UNITED STATES PATENT OFFICE

94,990

DESIGN FOR A GLIDER

John G. Rideout, Perrysburg, Ohio, assignor to
The Hettrick Manufacturing Company, Toledo,
Ohio, a corporation of Ohio

Application January 25, 1935, Serial No. 55,063

Term of patent 14 years

To all whom it may concern:

Be it known that I, John G. Rideout, a citizen of the United States, and resident of Perrysburg, county of Wood, State of Ohio, have invented a new, original, and ornamental Design for a Glider, of which the following is a specification, reference being had to the accompanying drawing, forming a part thereof.

In the drawing,

Figure 1 is a perspective view of the glider showing my design; and

Figure 2 is an end elevation of the glider shown in Figure 1.

I claim:

The ornamental design for a glider as shown.

In testimony whereof I have hereunto signed my name to this specification.

JOHN G. RIDEOUT.
